UNITED STATES PATENT OFFICE

EDWARD G. BUDD, OF PHILADELPHIA, PENNSYLVANIA, ASSIGNOR TO BUDD WHEEL COMPANY, OF PHILADELPHIA, PENNSYLVANIA, A CORPORATION OF PENNSYLVANIA

PILOT PIN FOR ROLLING MILLS

Application filed December 24, 1926. Serial No. 156,839.

This invention consists of a blank-centering pin for rolling mills for use in the type of mill shown in the patent numbered 1,606,903, dated November 16, 1926, for process and apparatus for forging metallic discs, by John W. Smith.

The above mentioned patent comprises a rotating platen on which blanks are centered and clamped for a rolling operation by radially-traversing rolls. The present invention avoids the necessity for such clamping means by providing a pilot pin to perform the centering and retaining functions of the clamp.

An object of this invention therefore, is the provision of simple and efficient means for aligning a blank with a supporting platen, and for preventing its rotation relative thereto.

Another object is the provision of an improved pilot pin, as hereinafter stated.

The invention is illustrated by the accompanying drawings, in which:

Figs. 1 and 2 are respectively, side and end views of the improved pilot pin;

Figs. 3 and 4 are similar views of a modified form thereof, and

Fig. 5 is a view, to a smaller scale showing the pin of Figs. 1 and 2 in place in the platen of a rolling mill of the type specified.

The improved pilot pin, which serves in place of the clamping means of the said patent comprises broadly a removable center for the platen and is designated generally, in the several figures, by the numeral 2. In Fig. 5, the platen is indicated at 1. The pin being removable, can be made of harder and more durable material than the platen to provide for the extra wear which it must undergo.

More specifically, the pin 2, Figs. 1 and 2, comprises a threaded end 10, a body 12, lugs or flutes 13 and a nib or point section 16.

The threaded end 10 and the cylindrical body 12, supplemented by a shoulder 11 therebetween, serve with the cooperating and mating portions of the pin seat in the platen, to position the pin in proper relation to the platen surface. A relieved portion

11' between the said shoulder and the threads ensures full engagement of the pin in the platen.

With the pin properly positioned in its seat the surface 12' is flush with the surface of the platen. The cruciform lugs or flutes 13 provide keys, lying in the plane of the blank, when the latter is in place on the platen. The said lugs extend radially outward at uniformly spaced intervals, (in the instances shown there are four lugs) from a relatively smaller prolongation 15 of the body 12. Complementary notches are provided about a central orifice in the blank adapted to fit the lugs 13 and the body extension 15.

The end faces 14 of the lugs 13 are beveled off, as shown, to facilitate the engagement of the orifice in the blank with the above-described retaining portion of the pin. Above the surfaces 14 the body 15 extends for a short space, and then merges into a blunt, conical point or nib 16.

From the above description, it is apparent that the operator of the machine equipped with the improved pilot pin need only engage the nib 16 of the pin with the pre-formed central aperture of the blank, and then release the blank. The weight of the latter will cause it to fall into engagement with the lugs 13, where it is aligned with the axis of rotation of the platen and securely held against rotation relative thereto.

The modification shown in Figs. 3 and 4 differs from the above only in the radial extent of the lugs or plates 13. This feature of Figs. 3 and 4 would be desirable where the forces to be resisted by the pin are excessive, as where large reductions of the thickness of the blank were contemplated, or difficult material to be worked.

What I claim is:

1. A centering and retaining pilot pin for a rotating rolling mill platen, comprising a substantially cylindrical body providing locating means, a threaded extension of said body providing securing means, lugs projecting from said body in cruciform arrangement and having beveled surfaces, relieved oppositely to the direction of rotation, and

a blunt, tapered elongation of said body, concentric therewith and with said lugs of different cross section.

2. A work centering and retaining pilot pin for rolling mills polygonal in cross section and having certain of the polygonal surfaces relieved oppositely to the direction of rotation.

3. As an article of manufacture, a centering and retaining pilot pin for rolling mills comprising a retaining portion polygonally formed, the surfaces of which are relieved in a direction opposite to the direction of rotation, an entry portion of less decided polygonal form and tapering longitudinally, and a screw threaded locating and securing shank of cylindrical form.

4. In combination, a rotatable rolling mill platen, and a work centering and retaining device therefor comprising a pin having one end portion held in said platen, a second portion beyond the surface of said platen and with rough peripheral contour whereby work may be held thereon against rotation with respect thereto, and a third portion comprising a tapered outer end.

5. A work centering and retaining device for a rotatable rolling mill platen, said device comprising a pin polygonal at one portion and having at one end a blunt tapered point of different cross-section than the polygonal portion, and at the end opposite to said tapered point a portion adapted to be held in a platen.

6. A work centering and retaining device for a rotatable rolling mill platen, said device comprising a pin having one end portion adapted to be held in a platen, a second portion of rough peripheral contour whereby work may be held against rotation with respect to said pin, and a third portion at the opposite end from said first portion and including a tapered end.

7. A work centering and retaining device for a rotatable rolling mill platen, said device comprising a pin having one portion adapted to be held in a platen, a second portion of cruciform cross-sectional contour whereby work may be firmly held against rotation relative to said pin, and a third portion comprising a tapered outer end.

8. A work centering and retaining device for a rotatable rolling mill platen, said device comprising a pin having one portion adapted to be held in a platen, a second portion next adjacent said first portion and having laterally extending lugs whereby work may be held against rotation relative to said pin, and a third portion including a tapered outer end.

In testimony whereof he hereunto affixes his signature.

EDWARD G. BUDD.
